F. MANKEY.

PANEL.

No. 16,235.

Patented Sept. 8, 1885.

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,235, dated September 8, 1835.

Application filed July 18, 1835. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

My design is intended for an open-work ornamental panel. It consists of rows of octagonal figures A, disposed lengthwise and transversely the panel. Between said figures are rectangular openings B. Extending longitudinally above said figures A are bars C.

Upon said bars appear transverse incised lines 15 or scores D, above the meeting sides of the octagons.

I claim—

The design for an open-work panel, substantially as herein shown and described, consisting of the octagonal figures A, disposed in rows, with intermediate rectangular openings, B, and longitudinal bars C. 20

FREDERICK MANKEY.

Witnesses.
